MACHINE FOR GRINDING OBJECTS

Walter H. Catucci, Kearny, N. J.

Application June 15, 1946, Serial No. 676,941

4 Claims. (Cl. 51—79)

1

This invention relates to a method of and machine for grinding objects. It is particularly directed to the grinding of objects of small size, to provide the same with shouldered portions or portions of reduced diameter—for example, to provide wire members, originally of uniform diameter, with stem portions of reduced diameters.

Such wire members are used in large volume in the textile and other industries, in sound reproduction (as phonograph needles) and for analogous purposes.

The invention herein set forth provides for the rapid grinding of such objects in an accurate manner and with a high quality of finish at low cost, and fills a long-felt want in the industry for a method and apparatus attaining these objectives.

An embodiment of a structure employing my invention is shown in the accompanying drawings and described in detail in the ensuing specification. This embodiment is merely by way of example and my invention is not limited thereto but includes all other forms which would come within the scope of the appended claims. In the drawings,

Fig. 1 is an end elevational view, partly fragmentary, of a machine embodying my invention, said view being taken at the point indicated by the designation and arrow "Fig. 1" in Fig. 3,

Fig. 2 is an enlarged, fragmentary view of the grinding wheel of my machine shown grinding or shouldering the wires or pins which are rotated by the wire feed roller upon the saddle member,

Fig. 3 is a side elevational view of the machine taken at the point indicated by the designation and arrow "Fig. 3" in Fig. 4,

Fig. 4 is a top plan view of said machine, taken at the point indicated by the designation and arrow "Fig. 4" in Fig. 3,

Fig. 5 is a fragmentary, vertical view, partly sectional, showing the peripheral edge of the wire feed roller and the shaft on which the same is mounted and showing the saddle member, partly sectional,

Fig. 6 is a fragmentary plan view of a wire member or other object to be ground pursuant to my invention, and

Fig. 7 is a similar view of said object after the operation of grinding the same pursuant to my invention.

The drawings illustrate the application of the invention to the grinding or shouldering of wire members 10 which initially have the flat ends 11.

The modus operandi of the invention may be noted from Figs. 1 and 2. The wire members, designated by the generic numeral 10 in Fig. 1 and by the reference characters 10a—10i in Fig. 2, are initially deposited in the hopper 24, where they are fed to the preferably resilient periphery

2

15 of the wire feed roller 14 which impinges on the wire members, rotating them in the direction indicated by the arrows 16, Fig. 2, on the preferably resilient cover 17' of the saddle 17, and advancing them as indicated by arrow 22, toward the discharge end 17a of the saddle and into my suitable collecting receptacle.

The surface of saddle 17 is preferably arcuate and concentric with the periphery of the feed roller 14; as above stated, said concentric surfaces are preferably resilient; they are preferably spaced apart to define therebetween a space slightly less than the diameter of the wire members 10 or other objects to be rotated therebetween and advanced in the direction of arrow 22, Fig. 2. The saddle 17 is provided with means, hereinafter more fully described, whereby it may be advanced or retracted relative to the periphery of the feed roller 14, to accommodate wire members or other objects of various diameters.

During the rotation of the wires by the feed roller 14, they are engaged by grinding wheel 19 which rotates in a direction transverse to the longitudinal axis of said wire members, and, as indicated by the arrow 21, Fig. 2, in a direction opposite that of feed roller 14. The grinding wheel 19, as will be presently explained in greater detail, is mounted or otherwise juxtaposed eccentrically with respect to the axis (23, Fig. 2) defined by the advancing wires, and preferably has a cylindrical periphery. Thus, the wires are advanced between two gradually converging and circular arcs defined by the circular base or saddle 17 (which is generally arcuately parallel to the circumference of the wire feed roller 14) and the periphery of the grinding wheel 19, which is eccentrically mounted relative to the wire feed roller 14. The wires are thus subjected to progressively greater grinding action of the grinding wheel 19 as they advance to the discharge end 17a of the saddle 17. By the method and apparatus above described, the wires are smoothly, uniformly and rapidly provided with shoulders 12 and with stem portions 13, of predetermined diametrical reduction (Figs. 2 and 7) which may be controlled, as hereinafter explained, to a high degree of accuracy, while maintaining a maximum of production, at low unit cost. The minute diametrical reduction thus effected on each wire for each revolution thereof produces a most satisfactory and fine degree of high finish.

Grinding wheel 19 is keyed to the shaft 33 which rotates in journals 32 integral with the slide 34. The drive shaft 33 may be rotated by a power source such as main electric motor 26, through any suitable power transmission means, as by pulley 27 driven by the armature shaft of the motor 26, and belt 28 entrained over driven pulley 29 keyed to the shaft 33 of the grinding

wheel. The grinding wheel may be advanced or retracted relative to the center of feed roller 14 (and thus also to the axis 23 defined by the advancing wire members) by rotating the hand-wheel 34 at the lower end of slide 31. The longitudinal axis of slide 31 is shown to extend at right angles to the plane which is tangent to the grinding wheel 19 at the point where it is closest to the saddle 17, as will be understood from Fig. 1. The graduated dial 35 of slide 31 allows the careful registration of the slightest motion of the slide and grinding wheel 19, and enables the operator to adjust the apparatus to provide the wire members with ground, reduced stem portions 13 of extreme accuracy.

The slide 31 is supported at an acute angle to the horizontal machine pan 49 by frame 38, the latter being mounted on horizontal shafts 36, 37, mounted in the journals 39, 40, 39', 40' (see Fig. 4). Thus, when the grinding operation is being set up, the grinding wheel 19 and associated parts can be moved away from the wire feed roller 14.

The shaft 43 of wire feed roller 14 rotates in journals 41, 42 carried by portions 55' of frames or supporting members 56, said shaft 43 being driven by any desired or convenient power source, such as a small auxiliary motor 46, through any desired or convenient power transmission means, such as, the following: Bevel gear 47, keyed to armature shaft of motor 46, meshes with and drives bevel gear 48 of the vertically journaled shaft 48', to the upper end of which worm 45 is keyed. Worm 45 meshes with and drives worm gear 44 keyed to the shaft 43 of wire feed roller 14.

If desired, means may be provided for elevating and lowering the saddle 17 to accommodate objects of various sizes and diameters. For example, a sub-base 52 for saddle 17 may be mounted on the machine pan 49 (see Fig. 5) with a wedge member 53 interposed between the saddle 17 and sub-base 52. The wedge 53 may be engaged by push-pull screws 54 of the bracket 55 (see Figs. 1 and 4) to adjust the position of saddle 17. Machine pan 49 may be provided with legs 50, and with a receptacle 51 to hold the fluid lubricant.

Having thus described my invention what I claim as new and desire to secure by Letters Patent is:

1. A machine for grinding the ends of small metal objects having a cylindrical form, comprising a saddle having a concave resilient surface, a feed roller whose axis of rotation is coaxial with the concave resilient surface of the saddle, said feed roller having a cylindrical periphery the surface of which is also resilient and is spaced from the concave resilient surface of the saddle a distance slightly less than the diameters of the small metal objects, means to feed the small metal objects to the space between the saddle and feed roller, the resilient surface of the saddle and feed roller yielding slightly in the passage of the small metal objects along said space between the saddle and the feed roller thereby effecting continuous rotation of each of the small metal objects on its axis during said passage, a grinding wheel having its axis of rotation slightly eccentric to the axis of the feed roller so that part of its periphery is nearer to

the saddle than the feed roller, and means to drive both the feed roller and the grinding wheel, the parts being so constructed and arranged that as the small metal objects are rolled along the space between the feed roller and the saddle the grinding wheel will grind the ends thereof and will progressively reduce said ends until the desired reduction in size of said ends is effected.

2. The invention as defined in claim 1, wherein the grinding wheel has a cylindrical periphery and is so set as to grind the ends of the small metal objects to form still smaller cylindrical stems, the direction of rotation of the grinding wheel being opposed to the direction of travel of the small metal objects between the saddle and the feed roller.

3. A machine for grinding the ends of small metal objects having a cylindrical form, comprising a machine frame, a feed roller, object-feeding means discharging the objects to the feed roller, means to rotate the feed roller, an arcuate stationary saddle having a discharge end and spaced slightly from the periphery of the feed roller, said saddle and feed roller having co-operating opposed resilient surfaces for direct engagement with the objects, the feed roller rolling said objects on their axes from the discharge end of the feeding means to the discharge end of the saddle, a grinding wheel arranged eccentrically relative to the saddle and feed roller, means to rotate the grinding wheel in a direction opposed to the direction of travel of said objects, said grinding wheel engaging the objects at their ends and progressively reducing said ends to smaller cylindrical stems as said objects roll between the feed roller and the saddle, and manually controlled means on the machine frame adapted to shift the axis of rotation of said grinding wheel toward and from the saddle, said manually controlled means permitting a fine adjustment so that minute changes in the dimensions of the reduced ends of said objects may be effected.

4. The invention as defined in claim 3, wherein said manually controlled means comprises a slide, means to mount the slide on the machine frame, a handwheel adapted when rotated to move the slide longitudinally, a graduated dial on the slide permitting measurement of the smallest motion of the slide and hence of the grinding wheel, the slide extending at an acute angle to the horizontal and at right angles to the plane which is tangent to the grinding wheel at the point where it is closest to the saddle.
